Attorney.

UNITED STATES PATENT OFFICE.

EDWARD N. WOOD, OF CHICAGO, ILLINOIS.

WALL CONSTRUCTION.

1,307,767.

Specification of Letters Patent. Patented June 24, 1919.

Application filed January 10, 1916. Serial No. 71,240.

To all whom it may concern:

Be it known that I, EDWARD N. Wood, a citizen of the United States of America, residing at Chicago, in the county of Cook 5 and State of Illinois, have invented certain new and useful Improvements in Wall Construction, of which the following is a specification.

This invention relates to wall construction 10 and more especially to the construction of laterally bonded walls.

In ordinary brick wall construction the wall is built up of sets of layers or courses 15 of brick arranged longitudinally of the wall in superposed tiers and known as "stretchers." These sets are separated, one from the other, by single courses of brick laid transversely of the wall and known as "headers." The several bricks are held together by some 20 cementitious material such as mortar, cement, or the like, or by fire clay.

Walls, and especially furnace walls, boiler settings and other like walls subjected to 25 high degrees of heat, are found to rapidly deteriorate when thus constructed, the deterioration taking the form of separation of one tier of stretchers from the adjacent tier by reason of the insufficient adhesion between 30 the relatively smooth surface of the bricks of the headers and adjacent stretchers and the cementitious joint-filling material. This insufficient adhesion is further impaired by the disintegration of the thick joints of mortar under the influence of the high temperature 35 of the furnace.

The principal object of the invention is 40 to provide an improved wall construction which will prevent such separation of the different tiers, the construction being such that only bricks and cementitious material 45 are used in the wall, no metallic bonding being required.

In boiler settings and furnace walls especially it is found that the tier of bricks next 45 to the fire (generally fire brick) is prone to separate from the remainder of the tiers when the wall is constructed in the common manner. This is caused by the unequal expansion of the fire and common brick, and 50 by the wedging action of the disintegrating mortar and clay in sifting downward into the opening joint and packing under the vibration of the wall, alternately resisting the effort to return to normal position under 55 lowering of temperature and still further fill-

ing and packing as the wall opens out under increase of temperature. Owing to the disintegration of the mortar and clay surrounding that part of the fire brick header projecting into the wall, the fire brick lining 60 becomes practically independent of the support of the adjacent wall, making it sensitive to the overturning wedge action of the silting mortar and clay.

A second important object of the invention 65 is to provide means for interlocking the headers in the tier next the fire or heat with headers in the interior of the wall so as to prevent such separation as above referred to.

In party walls between furnaces and the like both of the outer tiers are thus exposed 70 to intense heat and a third important object of the invention is to provide a wall wherein all the tiers will be held together by mechanically interlocked headers.

With the above and other objects in view, as will be hereinafter apparent, the invention consists in general of certain novel constructional arrangements and improved 80 details hereinafter fully described, illustrated in the accompanying drawings and set forth in the claims.

In the accompanying drawings like characters of reference indicate like parts in the 85 several views, and:

Fig. 1 is a cross section through a boiler setting showing an outer and a partition wall constructed in accordance with 90 this invention.

Fig. 2 is an enlarged detail view of one form of bond for a wall constructed in accordance herewith.

Fig. 3 is a partial cross section through a six tier wall bonded from side to side in 95 accordance herewith.

Fig. 4 is a detail view of one form of header or locking brick.

Fig. 5 is a detail view showing two bricks of modified form interlocked.

Fig. 6 is a view similar to Fig. 5 but illustrating a second modification of the form of the header locking bricks.

Fig. 7 is a view of the wall constructed in the ordinary manner, the wall being 105 shown in cross section, and the separation of the fire bricks from the body of the wall being indicated.

As illustrated in Fig. 1, a wall built up in accordance with this invention consists of 110

a series of courses each composed of longitudinally extending bricks 10 and these courses are arranged in sets which are separated by headers, as will be hereinafter described. In Fig. 1 a boiler setting has been indicated wherein a lining of fire brick as indicated at 11 is employed, the brick 10 being of common variety such as the ordinary red clay brick. In separating the different sets of stretchers it is preferred to employ, in some instances, headers 12 of red brick and only use a single locking header 13. This is permissible by reason of the fact that the mortar which is mechanically locked to such locking header will have a very considerable degree of adhesion to the porous red brick, while if the locking header was made of the ordinary smooth form, the mortar would not properly adhere to the smooth fire clay brick. It is to be noted that the headers, such as indicated at 13, may be of the form shown in Fig. 4, wherein one face of the brick is provided with a prismatic projection 14 and a prismatic recess 15 or they may be of the form shown in Fig. 5, wherein one face of each is provided with corrugations 16. As a variant the headers may have their faces serrated as shown at 17 in Figs. 6 or they may be of any other form which is found desirable. In connection with such headers I preferably provide half-headers 18 which have their faces next to the irregular face of the header formed to interlock therewith, such construction being clearly shown in Figs. 1 and 2.

A second manner of using the locking headers is illustrated in the outer wall of Fig. 1 and is preferably used at the center of height of such a wall where the tendency to bulge and separate is greater. In this arrangement one of the locking headers is bedded in the center of the wall as illustrated at 19, while a second header 20 interlocks therewith so that there is a greater amount of resistance to any tendency of the lining of the fire brick to separate from the balance of the wall. Where party walls are employed as shown in Fig. 1 it is advisable to interlock the parts so that both of the outer faces of the wall are mechanically locked together. This is effected by employing a lower course of interlocking headers 21 and an upper course of interlocking headers 22 locked with the headers 21 mechanically as illustrated and extending in the two courses from side to side of the wall. In Fig. 1 a four tier and a five tier wall are illustrated while in Fig. 3 a six tier wall is illustrated and in this instance it is necessary to cut off half of certain of the headers at the ends, the portion removed being illustrated by the dotted outline at 23. This thorough tying of the ties is also illustrated at 21 and 22 of the outer wall of Fig. 1.

65 It is obvious that this construction is not

restricted to furnace walls or to walls of composite nature, but may be used with walls made entirely from the same class of brick but it is found especially valuable to use the construction where facing brick of any class are to be bonded to a wall constructed mainly of an inferior grade of brick.

In furnace work it is found that the tendency of fire brick lining is to separate from the body of the wall by detachment of the headers and inward bulging of the fire brick lining as clearly illustrated by the lining of Fig. 7. This is occasioned by the fact that there is a different coefficient of expansion in fire and ordinary brick as well as by the fact that the inner tier or lining is exposed to a much more intense heat than the outer tiers and that, clay in the form of brick being a poor conductor of heat, the outer tiers of the wall remain practically cold, while the inner tier may have its face at a red heat.

It is to be observed from the foregoing that this construction provides for the secure mechanical bonding of the facing tiers of bricks in a wall to the body of the wall and that the construction can be utilized for bonding all of the tiers from side to side and all this without the use of any metallic bond or extra parts other than the brick and cement utilized to build the wall itself.

What I claim as new is:—

1. A wall structure comprising stretchers of flat-faced bricks, headers of bricks interposed between the bricks of the stretchers, and a binder between adjacent faces of the bricks of the stretchers, said bricks of the headers being of uniform configuration and having one transversely uniformly undulated face, the remaining faces being flat, and said header bricks being arranged in superimposed offset interlocking relation presenting unmatched portions with depressions receiving the binder therein to anchor the headers in the structure between the stretchers.

2. In a wall construction, the combination of the usual flat-faced bricks secured together by mortar in the usual manner, with tie members of uniform configuration substantially conforming to the form of said bricks interposed in the wall structure between said bricks, each having all except one face flat, the one being uniformly transversely undulated, and said tie members being arranged in superimposed offset interlocking relation presenting unmatched portions with depressions receiving the mortar therein to anchor the tie members in the wall structure.

3. In wall construction, the combination of stretchers formed of the usual flat faced bricks, and a binder securing said bricks together, of headers arranged between the

- stretchers and each comprising two layers of
bricks of the usual thickness and size of the
bricks in the stretchers and provided with
interfitting contacting faces and outer flat
faces for contact with the mortar of the
stretchers, said layers of the heading being
arranged in longitudinally overlapping re-
lation with the projecting end of one of the
layers interfitting in the bricks of the
stretchers and having the corrugated face
thereof embedded in the mortar of the
stretchers to anchor the headers therein.
4. A composite structural wall having a
facing of fire brick and a core of plain brick
and consisting of a multiplicity of elon-
gated units of uniform size arranged as
courses of stretchers and headers, said units
being united by coherent material, certain of
said units of the headers and the facing
having interfitting contacting faces to me-
chanically interlock the facing to the head-
ers, the units of said headers having inter-
fitting abutting faces and being arranged in
overlapping relation, the inner ends of the
headers being interfaced between the plain
bricks of the core and the coherent material
being embedded in the exposed interfitting
faces of the headers.
5. In a building construction, a bonding
block of substantially rectangular form
having five flat faces and provided on the
remaining face with a transverse depression
and a complemental transverse projection,
the projection and depression being spaced

substantially equi-distant between the ends 35
and center of the face at opposite sides of
said center, whereby two similar blocks may
be interlocked in offset relation with the
projection of one block interfitting with the
recess in the other block. 40

6. A bonding block of substantially rec-
tangular form having a single transverse
projection on one face intermediate one end
and the center thereof and a single depres-
sion in said face intermediate the other end 45
and said center of a form to fit said pro-
jection, the remaining faces of said block
being flat.

7. A wall structure including stretchers
of flat-faced bricks, headers of bricks inter-
posed between the bricks of the stretchers,
said bricks of the headers being of uniform
configuration, each having one uniformly
undulated face and arranged in superim-
posed offset interlocking relation to present 55
unmatched portions, and bricks constituting
portions of the bricks of the headers inter-
locked with the unmatched portions to finish
the facing tier of the structure.

8. A bonding block of substantially rec- 60
tangular form, all but one of whose faces are
flat, the one face being uniformly trans-
versely undulated to form a depression alter-
nating with a complemental non-overhang-
ing projection, each extending entirely 65
across the block.

In testimony whereof I affix my signature.
EDWARD N. WOOD.
